WORKSTAND

William E. McDonald, Salt Lake City, Utah

Application September 7, 1945, Serial No. 615,061

8 Claims. (Cl. 100—31)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to a stand for use in conjunction with a gravity or power-driven roller conveyer, for performance of work on an object placed on the conveyer without removing it therefrom, such as nailing or banding a box placed on the conveyer.

An object of my invention is a conveyer section which enables the operator to lift the load out of contact with the moving conveyer rollers, in order to perform work thereon.

Another object of my invention is to provide reliable support for the load while out of contact with the conveyer rollers.

Still another object of my invention is the provision of guides for a strapping wire or band, as an integral part of the section.

Another object of the present invention is a load-lifting device adapted for association with a conveyer, enabling the operator to perform work on an object, such as a box, on the conveyer line, without having to remove it therefrom.

Yet another object of my invention is a device for lifting a load above the conveying surface of belt-driven rollers, without interfering with the rotating belt.

A further object of my invention is a conveyer section, capable of carrying out the foregoing objects, which can be cheaply and sturdily constructed, and easily installed as an integral part of a gravity or power-driven conveyer line.

A conveyer section according to my invention consists of a section of belt-driven rollers, a vertically movable frame straddling the section, a number of transverse load-supporting boards positioned in the interstices between the rollers, and supported by the movable frame, and treadle-actuated means for vertically lifting the movable frame, thereby raising the load-supporting surfaces above the rollers. Two arcuate channel-shaped guides for wire or strap banding, in place of two of the transverse boards, curve outwardly and upwardly from the conveyer section.

The accompanying drawings illustrate a preferred embodiment of my invention.

Figure 1 is a perspective view of a banding stand in a conveyer section in accordance with my invention.

Figure 2 is a plan view of the conveyer section shown in Figure 1.

Figure 3 is a front elevation thereof with parts broken away and in section.

2

Figure 4 is an end view corresponding to Figures 2 and 3.

Figure 5 is a fragmentary detailed sectional view along lines 5—5 in Figure 3.

Figure 6 illustrates diagrammatically a box supported above and out of contact with the conveyer rollers, for the performance of banding operations.

Figure 7 shows diagrammatically a box illustrated in Figure 6, lowered on the conveyer rollers for further transportation after completion of the banding.

In the drawings, 11 is the main conveyer, which may be of the gravity or power-driven roller or of the chute type. 12 is the fixed frame of the special conveyer section preferably made of L-beams, and carrying a plurality of load-conveying rollers 13, and is substantially of the same width as the main conveyer line with which it is to be used. The length of frame 12 is determined in accordance with the size of the boxes or other loads which are to be worked on. A second frame 14, preferably of inverted L-beams, straddles frame 12, and a number of transverse boards 15 are mounted on frame 14; the transverse boards 15 are spaced from and disposed between rollers 13. Frame 14 is movably supported by four legs 16 which, in the embodiment illustrated, pass through holes in horizontal flanges in frame 12. (See Fig. 5.) The lowermost portions of legs 16 consist of toggles 17, 17' pivotally supported on the ground. Two rockers 18, 18' are each connected to a pair of toggles 17, 17' by a pair of links 19, 19', each link joining an outer end of rocker 18 (or 18') to the joint of toggle 17 or 17', respectively. Rockers 18 and 18' are fast on horizontal shaft 20, which rests in bearings 21, 21'. Two operating levers 22, 22' extend tangentially from shaft 20 and are fast thereon. The two levers 22, 22' are joined by a treadle bar 23. A helical spring 24 is fastened at one end to the outer end of lever 22, and at its other end is fastened to frame 12; correspondingly a spring 24' is fastened to the outer end of lever 22' and to frame 12.

Because of the normally raised position of levers 22, 22' by means of springs 24, 24', the rockers 18, 18' and links 19, 19' push toggle links 17, 17', into an almost straight position, whereby legs 16 and frame 14 are elevated and the load-supporting transverse boards 15 are raised above the conveyer surface of rollers 13; this is illustrated in solid lines in Figure 4.

An endless belt 25 is in contact with the lower surface of rollers 13 for the purpose of actuating

them; belt 25 is power-driven, and is tensioned by auxiliary rollers 26.

Two of the transverse boards 15 are substituted for by guides 27, 27' for a metal wire or a strap, designated W in Figures 6 and 7, for application to a box designated B in Figures 6 and 7. The guides 27, 27' are channel pieces whose upper edges terminate on the same level as the upper surfaces of transverse load-supporting boards 15. Guides 27, 27' extend outwardly beyond frame 14 and curve upwardly, so that the operator may insert a wire or strap from a coil (not shown) into the guide and bring it forward under the box and upward to complete the strapping operation.

The conveyer section is joined to the main conveyer line 11 by bolting frame 12 thereto at 28.

In operation the operator depresses treadle 23 when he sees box B approaching, thereby buckling the toggles 17, 17' and lowering legs 16 and frame 14. This causes transverse boards 15 and the horizontal portion of guides 27, 27' to descend below the load-conveying surface of rollers 13 as shown in broken lines in Figure 4. The downward vertical movement of boards 15 is limited by their coming to rest on frame 12. When box B has arrived in its proper position above frame 14 and boards 15, the operator releases treadle 23. Springs 24, 24' now pull up levers 22, 22', thereby rotating the shaft 20 several degrees, which causes rockers 18, 18' to 30 straighten toggles 17, 17' in synchronism, and to push up legs 16 and frame 14 so as to lift boards 15 and box B above and out of contact with rollers 13. Box B is now supported in a stationary position, while the operator performs the nailing or banding operation, the latter with the help of guides 27, 27'. After completion of the operation, the operator again depresses treadle 23, thereby lowering box B into contact with the rotating rollers 13, which carry box B from the banding stand and permit it to proceed on the main conveyer line. The stand is now ready for the arrival of a new box.

While I have in the foregoing described the construction and operation of a preferred embodiment of my invention, I do not wish to be limited to any specific details of construction and operation set forth therein, inasmuch as modifications within the principles and spirit of my invention will readily occur to the expert. I desire to claim my invention broadly and to be limited only by the appended claims.

I claim:

1. In a conveyer of the type comprising a frame, rollers carried by said frame and a power-driven endless belt in frictional engagement with the lower surfaces of said rollers: a stand straddling said frame and comprising vertically movable non-rotating load-supports parallel to said rollers between and spaced from said rollers for lifting a load above and out of contact with the conveying surfaces of said rollers, vertical reciprocatory means laterally spaced from said rollers and belt for vertically moving said load-supports, said means being operable independently of and without affecting the movement of said rollers and operation of said belt, and means affixed to said frame for positively urging said stand upwardly relative to said frame; whereby a load conveyed by said rollers to a position above said stand may be lifted by said stand above and out of contact with said rollers, and whereby said load-supports may be retracted within the spaces between adjacent rollers.

2. In a conveyer of the type comprising a

frame, rollers carried by said frame and a power-driven endless belt in frictional engagement with the lower surfaces of said rollers: a stand straddling said frame and comprising vertically movable non-rotating load-supports parallel to said rollers between and spaced from said rollers for lifting a load above and out of contact with the conveying surfaces of said rollers, toggle legs laterally spaced from said belt for vertically moving said rollers and load-supports, said toggle legs supporting said load-supports and being operable independently of and without affecting the movement of said rollers and operation of said belt and means for selectively straightening and buckling said toggle legs, and means affixed to said frame for positively urging said stand upwardly relative to said frame; whereby a load conveyed by said rollers to a position above said stand may be lifted by said stand above and out of contact with said rollers, and whereby said load-supports may be retracted within the spaces between adjacent rollers.

3. In a conveyer of the type comprising a frame, rollers carried by said frame and a power-driven endless belt in frictional engagement with the lower surfaces of said rollers: a stand straddling said frame and comprising vertically movable non-rotating load supports parallel to said rollers between and spaced from said rollers for lifting a load above and out of contact with the conveying surfaces of said rollers, at least one of said non-rotating load supports comprising a channel-shaped upwardly curving guide for a band or wire to be applied to the load, vertical reciprocatory means laterally spaced from said rollers and belt for vertically moving said load supports, said means being operable independently of and without affecting the movement of said rollers and operation of said belt, and means affixed to said frame for positively urging said stand upwardly relative to said frame; whereby a load conveyed by said rollers to a position above said stand may be lifted by said stand above and out of contact with said rollers, and whereby said load-supports may be retracted within the spaces between adjacent rollers.

4. In a conveyer of the type comprising a frame, rollers carried by said frame and a power-driven endless belt in frictional engagement with the lower surfaces of said rollers: a stand straddling said frame and comprising vertically movable non-rotating load supports parallel to said rollers between and spaced from said rollers for lifting a load above and out of contact with the conveying surfaces of said rollers, at least one of said non-rotating load supports comprising a channel-shaped upwardly curving guide for a band or wire to be applied to the load, toggle legs laterally spaced from said rollers and belt for vertically moving said load supports, said toggle legs being operable independently of and without affecting the movement of said rollers and operation of said belt, means for selectively straightening and buckling said toggle legs, and means affixed to said frame for positively urging said stand upwardly relative to said frame; whereby a load conveyed by said rollers to a position above said stand may be lifted by said stand above and out of contact with said rollers, and whereby said load-supports may be retracted within the spaces between adjacent rollers.

5. A conveyer section comprising a frame including a pair of spaced beams, load-conveying rollers carried by said frame, a load-supporting

frame of greater width than said first frame and including a pair of spaced beams parallel to the beams of said first frame, said load-supporting frame being vertically movable, means urging said load-supporting frame upwardly relative to said first-named frame, said means including spring means affixed to said first-named frame, vertically movable means supporting said load-supporting frame, and means for operating said vertically movable means; whereby a load conveyed by said rollers to a position above said load-supporting frame may be lifted above and out of contact with said rollers, and whereby said load-supporting frame may be lowered between said rollers and below the load-conveying surface of said rollers for advancement of said load by said rollers.

6. A conveyer section comprising a frame including a pair of spaced beams, load-conveying rollers carried by said frame, a load-supporting frame of greater width than said first frame and including a pair of spaced beams parallel to the beams of said first frame, said load-supporting frame being vertically movable, means urging said load-supporting frame upwardly relative to said first-named frame, said means including spring means affixed to said first-named frame, toggle legs supporting said load-supporting frame, a rocker, means connecting said rocker and said toggle legs, and a lever operating said rocker; whereby a load conveyed by said rollers to a position above said load-supporting frame may be lifted above and out of contact with said rollers, and whereby said load-supporting frame may be lowered between said rollers and below the load-conveying surface of said rollers for advancement of said load by said rollers.

7. In a conveyer, a frame, load-conveying rollers carried by said frame, a power-driven endless belt in frictional engagement with the lower surfaces of said rollers, a second frame straddling said first frame, said second frame being vertically movable, load-supporting means mounted on said second frame, said load-supporting means being substantially parallel to said rollers, at least one of said load-supporting means comprising a channel-shaped upwardly curving guide for a band or wire to be applied

5 to the load, spring means urging said load-supporting means to a position above said rollers, and length-adjustable means spaced from said belt supporting said second frame and adapted to selectively depress said load-supporting means below the load-conveying surfaces of said rollers and supporting said load-supporting means in a position above the load-conveying surfaces of said rollers.

- 10 8. In a conveyer, a frame, load-conveying rollers carried by said frame, a power-driven endless belt in frictional engagement with the lower surfaces of said rollers, a second frame straddling said first frame, said second frame being vertically movable, load-supporting means mounted on said second frame, said load-supporting means being substantially parallel to said rollers, at least one of said load-supporting means comprising a channel-shaped upwardly curving guide for a band or wire to be applied to the load, spring means urging said load-supporting means to a position above said rollers, two pairs of toggle legs spaced from said belt supporting said second frame and adapted to selectively depress said load-supporting means below the load-conveying surfaces of said rollers and supporting said load-supporting means in a position above the load-conveying surfaces of said rollers, two rockers, link means connecting each of said rockers with a pair of said toggle legs, an operating lever on each of said rockers, and a bar connecting said levers.
